UNITED STATES PATENT OFFICE.

FELIX VIGGERS, OF DES MOINES, IOWA.

AUTOMATIC STOKER.

1,227,707.

Specification of Letters Patent.

Patented May 29, 1917.

Application filed March 27, 1916. Serial No. 87,121.

To all whom it may concern:

Be it known that I, FELIX VIGGERS, a citizen of the United States, and resident of Des Moines, in the county of Polk and State 5 of Iowa, have invented a certain new and useful Automatic Stoker, of which the following is a specification.

The object of my invention is to provide an automatic stoker of simple, durable and 10 inexpensive construction.

A further object is to provide an automatic stoker comprising an endless grate, and having simple mechanism for operating the grate.

15 Still a further object is to provide such a grate of new and novel construction.

Still a further object is to provide means for mounting said grate.

A further object is to provide in such a 20 device means for controlling the draft to the fire and for supplying fresh air to the fire at the proper place.

My invention consists in the construction, arrangement and combination of the various 25 parts of the device, whereby the objects contemplated are attained, as hereinafter more fully set forth, pointed out in my claims and illustrated in the accompanying drawings, in which:

30 Figure 1 shows a front elevation of my improved automatic stoker.

Fig. 2 shows a side elevation of the same.

Fig. 3 shows a longitudinal, vertical, sectional view through my improved stoker.

35 Fig. 4 shows a transverse, vertical, sectional view taken on the line 4—4 of Fig. 3.

Fig. 5 shows a detail view of part of the grate operating mechanism, and

Fig. 6 shows an inverted plan view of one 40 of the grate sections.

In the accompanying drawings, I have used the reference numeral 10 to indicate the furnace body. The front wall 11 has a variety of openings for the purpose, herein- 45 after mentioned.

I have shown my improved automatic stoker used in connection with a boiler 12.

I provide in the interior of the side walls 10 of the furnace on each side thereof, a 50 guideway, composed of two elliptical spaced strips 13, arranged concentric, the inner strip being continuous and the outer strip terminating at the front wall of the furnace.

The inner flange of each guide 13 projects 55 outwardly at the front of the furnace wall, and the outer flange of each guide 13 ter-

minates at the front wall of the furnace and permits the removal of sections of the grate.

My improved grate comprises in each case a series of grids or sections 15, one of which 60 is shown in inverted plan view in Fig. 6.

It will be seen that each grid 15 has on each side edge a plurality of fingers or projections 16. The fingers or projections 16 on one side of the grate section are staggered 65 with relation to those on the other side, so that the fingers 17 of the adjacent grate sections intermesh with each other.

At each end each grate section is provided with a pair of spaced rollers 17, adapted 70 to travel in the guides 13. Each grid is provided on its under side with a downwardly extending transverse rib 18, preferably arranged in the middle of the grid from front to rear. The grate sections are 75 slid into the guides from the front and pushed along until a continuous grate is completed.

At the rear of the furnace is a curved wall 19 adjacent to the inner end of the 80 grate.

A partition 20 extends from the lower end of the curved wall 19 downwardly and toward the front of the furnace. The upper rear end of the partition 20 stands just below and close to the grate, while the forward end thereof is spaced below the grate a suitable distance.

Above and below the forward end of the partition 20 are openings 21 and 22 in the 90 front furnace wall which may be closed by hinged doors 23.

I preferably arrange the doors 23 in pairs, each pair being arranged at the same height, so as to leave a vertical reinforcing member 95 24 in the center of the front wall of the furnace.

Opposite the front end of the grate are a pair of outwardly opening doors 25, which may be held closed by a suitable locking device 26. The doors 25 are fitted to the furnace front between the points of termination of the outer strips 13.

Above the upper front part of the grate is a chute 27 made in two halves divided 105 along a central vertical line. The halves are hinged at their side edges, as shown in Fig. 1, and may be locked in their closed position by means of the device 28.

Mounted in the side wall of the furnace 110 and extending transversely across the furnace between the upper and lower portion

of the grate is a crank shaft 29, having formed thereon within the furnace the cranks 30 and 30^a.

Pivotedly mounted on the crank 30 are arms 31 extending downwardly and forwardly in the furnace.

Pivotedly mounted on the cranks 30^a are arms 32 extending downwardly and rearwardly in the furnace, and having at their rear ends hook members 33 with their rear surfaces beveled at 33^a.

On the shaft 29 outside the furnace walls is a ratchet wheel 34.

Rotatably mounted on the shaft 29 adjacent to the ratchet wheel 34 is a bar 35 extending forwardly and rearwardly from the shaft 29. Pivoted to the forwardly extending portion of the bar 35 is a pawl 36 adapted to coat with the teeth of the ratchet wheel 34 and inclined upwardly and toward said ratchet teeth from the bar 35.

Pivoted to the rearwardly extending part of the bar 35 is a pawl 37 extending downwardly and toward the ratchet teeth and having an upwardly and rearwardly extending weighted end 38, whereby the pawl 37 is held in engagement with the teeth of the ratchet wheel.

Pivoted to the furnace wall above the ratchet wheel 34 is a pawl 39 adapted to engage the teeth of the ratchet wheel and prevent movement of said wheel in one direction.

Rotatably mounted on the shaft 29 adjacent to the ratchet wheel is a plate 40 having cam faces 42, adapted to be moved to position for engaging laterally projecting rollers 43 on the pawls 36 and 37.

Extending downwardly from the plate 40 is an arm 44 to which is pivoted a link or rod 45 extending forwardly and slidably mounted in the front wall of the furnace.

On the outer end of the link 45 is a handle 46. Pivoted between its ends on a bracket 47 of the front furnace is a lever 48. The inner end of the lever 48 is pivoted to the forward end of the bar 35. The outer end of the lever 48, outside the furnace is pivoted to the link 49, which is designed to be connected with any suitable source of power, whereby the lever 48 may be oscillated at certain predetermined intervals for oscillating the bar 35, and through the pawls 36 and 37 and the ratchet wheel 34 imparting rotation to the shaft 29.

The link 49 may be pivoted at different points to the lever 48 by means of plates or pins selectively extended through holes 50 in the outer end of said lever for regulating the stroke of the pawls 36 and 37. Further regulation of the action of said pawl is provided by manipulating the handle 46 for moving the plate 40 to different positions for causing the cam faces thereon to engage the rollers 43, whereby the pawls 36

and 37 may be held out of engagement with the ratchet wheel during part of the stroke of the bar 35.

In the practical operation of my improved automatic stoker, the fire is built on the upper portion of the grate and the coal is placed in the hopper 27. When the lever 48 is operated for rotating the shaft which can be either by machinery and automatically or if desired may be done manually, the shaft is rotated for turning the cranks thereon. It will be seen that during part of the movement of the shaft the arms 32 will be moved forwardly. The hooks 33, during such movement will engage the ribs 18, thereby moving the lower stretch of the grate forwardly, and the upper stretch rearwardly. During another part of the movement of the shaft the arms 31 will be moved forwardly in the machine, whereupon the arms 31 will engage the ribs 18, and move the lower stretch of the grate forwardly, thereby moving the upper stretch thereof rearwardly in the machine. During said latter movement the hooks 33 on the arms 32 travel rearwardly over the ribs 18, on account of the action of the cranks and the form of the beveled surfaces 33^a. It will be noted that on account of the construction and arrangement of the arms 31 and 32 and the cranks, the sections of the upper stretch of the grate will be kept close together, for holding the fuel and ashes, while sufficient play of the sections will be permitted in the lower stretch to allow for expansion and contraction.

Mounted inside the rear portion of the grate is a curved wall 51, which stands adjacent to the rear portion of the inside of the grate.

The upper portion of the wall 51 extends a short distance beneath the upper stretch of the grate, as clearly shown in Fig. 3.

The doors 23 may be opened to cause a draft, and on account of their arrangement and the arrangement of the partition 21 fresh air will be fed upwardly to the fire above the upper stretch of the grate along the entire length of the grate, except at the rear end thereof. It will be thus seen that fresh air is supplied to the burning coal for a considerable distance of its travel, and there is thereby secured a complete combustion.

I find that there is very little smoke which is not consumed by my furnace and automatic stoker.

The finer ashes drop downwardly through the grate upon the partition 20 and may be removed through the opening 21. The larger ashes pass rearwardly and drop downwardly over the curved wall 19 to the lower part of the furnace from which they may be removed through the opening 22. It will be seen that the grate sections are

of simple construction and may be quickly and easily repaired or replaced.

5 The use of the rollers 17 traveling in the guides 13 keeps the grate sections in their proper position, and permits of their travel with a minimum of friction.

10 I am also thus enabled to use comparatively heavy rollers on comparatively large spindles 17^a so that heat of the fire does not interfere with the travel of the grate.

15 Some changes may be made in the construction and arrangement of the parts of my improved stoker without departing from the essential features and purposes, and it 20 is my intention to cover by this application any such changes which may be included within the scope of my claims.

I claim—

25 1. In an automatic stoker, a furnace having side walls, a back and a front wall, parallel elliptical guide grooves spaced from each other, a grate comprising sections provided with pairs of rollers at their ends traveling in said grooves, each of said sections having on one side a transverse rib, a transverse shaft extending across the interior of said furnace between the upper and lower stretch of the grate having cranks, an arm pivoted to one of said cranks 30 and extending downwardly and forwardly to the lower stretch of the grate, an arm pivoted to another of said cranks and extending downwardly and rearwardly to the lower stretch of the grate having hook members with beveled rear surfaces, and means for rotating said shaft.

35 2. In an automatic stoker, a furnace wall, having a back, sides and a front, a pair of parallel guide grooves on the interior of the 40 opposite walls, a stoker comprising sections each having at each end a pair of spaced rollers mounted in said guides, a curved wall at the rear of said grate extending around the end thereof, a partition extending from 45 the lower part of said curved wall downwardly and forwardly to the front wall, a door in the front wall above said partition.

50 3. In an automatic stoker, a furnace having side walls, a back and a front wall, parallel elliptical guide grooves on opposite sides of the interior of the furnace, a grate comprising sections provided with pairs of

rollers at their ends traveling in said grooves, each of said sections having on one side a transverse rib, a transverse shaft extending across the interior of said furnace between the upper and lower stretch of the grate having cranks, arms pivoted to said cranks and extending respectively forwardly and rearwardly and downwardly to the lower stretch of the grate, means for rotating said shaft, said means comprising a ratchet wheel on said shaft, a bar pivotally mounted on said shaft, pawls pivoted to said bar and adapted to coact with said ratchet wheel, and means for oscillating said bar.

4. In an automatic stoker, a furnace having side walls, a back and a front wall, parallel elliptical guide grooves spaced from each other, a grate comprising sections provided with pairs of rollers at their ends traveling in said grooves, each of said sections having on one side a transverse rib, a transverse shaft extending across the interior of said furnace between the upper and lower stretches of the grate having cranks, an arm pivoted to one of said cranks and extending downwardly and forwardly to the lower stretch of the grate, an arm pivoted to another of said cranks extending downwardly and rearwardly to the lower stretch of the grate having at its end a hook member with a beveled rear surface, means for rotating said shaft, said means comprising a ratchet wheel on said shaft, a bar pivotally mounted on said shaft, pawls pivoted to said bar and adapted to coact with said ratchet wheel, and a plate pivotally mounted on said shaft having cam faces adapted to coact with said pawls for determining at what points in the stroke of the pawls said pawls shall engage the ratchet wheel.

5. In an automatic stoker, a furnace with walls, a substantially elliptical grate made in sections adapted to travel, said sections having transverse ribs, a shaft having a plurality of cranks within said grate, a plurality of arms mounted on said cranks and arranged when the shaft is rotated to engage said ribs for causing said grate to travel.

Des Moines, Iowa, March 18, 1916.
FELIX VIGGERS.
